UNITED STATES PATENT OFFICE.

DELIA NESGOOD, OF WEST BRIGHTON, NEW YORK.

SANITARY SUPPORT FOR NAPKINS.

1,103,815.

Specification of Letters Patent. Patented July 14, 1914.

Application filed September 24, 1913. Serial No. 791,611.

To all whom it may concern:

Be it known that I, DELIA NESGOOD, a subject of the King of England, residing at West Brighton, in the county of Richmond and State of New York, have invented new and useful Improvements in Sanitary Supports for Napkins, of which the following is a specification.

This invention relates to sanitary supports for napkins and it consists in the novel features hereinafter described and claimed.

An object of the invention is to provide a simple and substantial support which is adapted to effectually hold a napkin and from which the napkin may be readily detached when desired.

With the above objects in view the support comprises a sling of flexible water proof material which is folded longitudinally in the vicinity of its opposite side edges. Elastic members connect the folds together in the vicinity of the ends of the said sling and the napkin to be supported is adapted to be positioned in the sling under the said folds and under the said elastic members. The sling is provided at its ends with buttons or other suitable devices which may be connected in the ends 30 of straps and the said straps in turn are connected with a belt or band.

In the accompanying drawing:—Figure 1 is a perspective view of the support. Fig. 2 is an enlarged detailed view of a portion 35 of the same. Fig. 3 is a sectional view cut on the line 3—3 of Fig. 2. Fig. 4 is a similar view cut on the line 4—4 of Fig. 2.

The support comprises a sling 1 which is made from water proof flexible material and 40 which is provided in the vicinity of its longitudinal edges with folds 2. These folds are inwardly disposed toward each other

and are spaced from each other. Elastic members 3 are connected with the folds 2 at the ends thereof and the said elastic members serve to draw the folds at the opposite side portions of the sling 1 toward each other. 45

The napkin to be supported is inserted under the folds 2 and the elastic members 3 and rests upon the intermediate portion of the sling 1. The napkin so held may be readily detached from the sling and may be as readily inserted in position thereon. The sling 1 is provided at its corner portions 55 with buttons 4 which may be engaged with straps 5 attached to a belt 6.

The belt 6 is adapted to be passed around the waist and the straps 5 hang pendant so that when the buttons 4 are engaged 60 with the straps the sling is held in proper position with relation to the wearer.

Having described the invention what is claimed is:—

A napkin support comprising a sling of 65 flexible material folded in the vicinity of both of its longitudinal edges along two parallel lines whereby three plies of material are provided adjacent each longitudinal edge of the sling, the edges of both folds 70 lying within the longitudinal edges of the sling whereby single plies only are provided at the edge portions of the sling, and elastic members connected at their ends with the said folded portions at points where 75 the said material is arranged in three plies and at the outermost folds of the plies.

In testimony whereof I affix my signature in presence of two witnesses.

DELIA NESGOOD.
